UNITED STATES PATENT OFFICE.

OTTO VON BRONK, OF BERLIN-TREPTOW, GERMANY.

APPARATUS FOR THE ELECTRICAL TRANSMISSION OF PICTURES.

Application filed June 28, 1926, Serial No. 119,089, and in Germany July 6, 1925.

This invention relates to the electrical transmission of pictures and more particularly to means for carrying out the same.

The difficulties which have previously been encountered in attempting to effect a very rapid electrical transmission of pictures and the numerous proposals for avoiding these difficulties are well known from literature on the subject and from patent specifications.

10 No difficulties arise in the conversion of the picture elements into pulsating electrical currents by means of photo-cells and the transmission of these impulses along wires or by radio communication by means of carrier waves nor in very effective light control at the receiving station by means of the modern high frequency and amplifying devices. The chief obstacles, which arise in the construction of practically useful apparatus for instantaneous phototelegraphy or for electrical television, are the decomposition of the picture at the transmitting station and the synchronous phase-correct re-composition of the picture elements at the receiving station.

The present invention relates to a new apparatus for the rapid decomposition of a picture into its individual elements and for the synchronous re-composition of the picture elements at the receiving station. In contradistinction to a movable beam of light or equivalent means used for picture decomposition in the prior art, according to the invention a beam of parallel light rays which pass through one or more light controlling cells is used, which latter consist of a plurality of thin layers of an optically variable medium, the optical properties of the separate layers being electrically controlled in sequence. One or two of these cells are mounted at both the transmitting and receiving stations and are controlled synchronously by the same frequencies. The light from the picture to be transmitted is led through the two light controlling cells of the transmitter before it reaches the photo-cell. In a similar manner the rays from the light source at the receiving station influenced by the electrical impulses of the photo-cell are led through the two control cells mounted at that end and are controlled by these in a similar manner as at the transmitting station.

The known Kerr effect of electrical double-refraction can be used to effect this control by applying a plurality of condenser

plates between which is arranged a dielectric, being double refracting under the influence of electrical voltages. Care is taken in this respect that the individual condenser plates are electrically influenced in succession. The result obtained by means of the Kerr effect is that the horizontal and also the vertical series of picture elements pass through the Kerr cell in succession. If the frequency of the electrical control of the one control cell is many times greater than that of the second control cell located at right angles thereto the point of intersection at any moment of the series of picture elements travels over the whole surface of the picture and accordingly decomposes the picture into small area elements or units. Thus the individual lines of the picture are electro-optically controlled by the Kerr effect, i. e. are extinguished or brightened.

Instead of the Kerr effect the so-called Biot effect can also be used for the electro-optical control, that is the phenomenon well known in physics in which the optical properties of a medium transparent to light alter when the medium is subject to mechanical stress, more particularly when it is set in its natural vibration. Cady's experiments have shown that piezo-electric crystals can be excited by high frequency alternating current to perform their natural vibrations or harmonics thereof when there is resonance with the electric oscillations acting on the crystal. This piezo-electric effect which is especially noticeable in quartz but may also be observed in a number of other crystals, may also be used, according to the present invention, for the picture decomposition and re-composition by arranging thin laminae of quartz or other suitable material, cut exactly axially between the separate condenser plates of the cells instead of using nitrobenzole as in the Kerr cell. It is essential in this connection that each of the laminae super-imposed upon each other with intermediate coatings, should have a different natural vibration.

My invention is illustrated in the accompanying drawings in which

Figure 1 represents an explanatory diagram of the picture de-composing and re-composing method employed according to the invention, the diagram representing either the transmitting or the receiving station, as explained hereinafter;

Figure 2 represents diagrammatically the

connections of one of the two control cells 3 or 4 in Figure 1 with the source of alternating current in case the "Kerr effect" is used for these cells;

5 Figure 3 represents diagrammatically the manner in which the picture transmitted is divided into elements;

10 Figure 4 represents diagrammatically a control cell 3 or 4 in Figure 1, composed of oscillating crystal layers, together with their circuit connections;

Figure 5 represents a modified form of the cell shown in Figure 4;

15 Figure 6 represents a further modification of the cells 3 and 4 in Figure 1, with respect to the character of individual crystal laminae used, and

20 Figures 7 and 8 represent diagrammatically a picture transmitting system, Figure 7 illustrating the transmitting station and Figure 8 the receiving station.

25 Referring first to Figure 1 for the purpose of explaining the operating principle, parallel rays of light pass from the plane of the picture indicated by the arrow 1 through the polarizer 2, the cell 3 with vertical layers, the cell 4 with horizontal layers and the analyzer 5 of the Kerr cell and are brought to a focus 7 by means of the lens 6.

30 In the transmitting station at this point is located the photo-cell indicated by a rectangle around focus 7. This photo cell is located in an electric circuit, not shown in Figure 1, and transforms the light vibrations into electrical variations of current in the usual manner, so that the latter may be transmitted also in known manner by means of conductors or without wires to the receiving station.

40 The decomposition of the picture 1 into individual point-beams of light acting in succession on the photo-electric cell is effected by providing a passage for the light between the separate layers of the cell by 45 means of suitable electrical control of the layers of the cell in sequence. The successive opening up of the paths for the light through the cell 4 is however effected with much greater velocity than through the cell 50 3 so that for each release of one light passage through one layer in the cell 3, all the passages through cell 4 are opened successively through one layer after the other in the cell 4. Electricity affords a means of 55 carrying out this process in a fraction of a second.

A similar arrangement of the two control cells 3 and 4 as shown in Figure 1 is provided, as has already been mentioned, at the 60 receiving station. The difference between this and the transmitting station consists solely in arranging at the receiving end a source of light, (for example a point filament-tungsten-lamp) at the focus 7 of the lens 6 instead of a photo-cell and by con-

trolling its light intensity by the photo-currents received from the transmitter. A Kerr cell may for instance be arranged at the point 7 at the receiving station to act as such a light influencing device and would of course have the usual form of construction as in this case it only has to control the intensity of a strong source of light by means of the photo-currents arriving from the transmitting station. The rays of light thus altered in intensity at the point 7 of the receiving station are rendered parallel by the lens 6 and pass through the Nicol prism 5 which, in the receiving station acts as polarizer. The rays then pass through the two cells 4 and 3 and the Nicol prism 2 which now acts as the analyzer and so reaches the arrow 1 which then represents the screen. As the cells 4 and 3 at the receiving station are electrically controlled synchronously with the cells 3 and 4 of the transmitting station, the point of intersection between the horizontal and vertical layers has at any moment at the receiving station always the same relative position as that at the transmitting station and consequently only allows the intensities of light corresponding to that particular point in the original picture to reach the receiving screen.

95 In the purely diagrammatic example of Figure 1 the medium between the parallel condenser plates in cells 3 and 4 (for example nitro-benzole or the crystals) is omitted and also for the sake of clearness only five layers of an optically variable medium are shown in these cells. Of course, many more layers are necessary for the decomposition of the picture, for example for a decomposition into 10000 picture elements 105 the two cells each having 100 layers, which is easily possible to accomplish in practice, by using very thin layers. The polarizers or analyzers 2 and 5 consist preferably not of the natural calc-spar but of artificial 110 crystals of Chile saltpeter (sodium nitrate) which are very suitable and can be produced in large suitable pieces.

115 When a special Kerr cell is used at the receiving station at the point 7 in Figure 1 for the instantaneous light control then the analyzer of this cell, or in like manner the polarizer 5 of the device for decomposing the picture, can be omitted as the light proceeding from the Kerr cell 7 is already polarized.

120 Figure 2 shows the electrical connections of one of the two control cells 3 or 4 with a source of alternating current when the Kerr effect is used for controlling the cell. In this figure the group of parallel lines represents the cell.

125 One set of condenser plates α is in this case conductively connected directly with one pole of the source of alternating current W . A conductor leads from the other pole

of the source of alternating current W to the plates of the other set through impedances such as coils or resistances c, d, e, the dimensions of which impedances are graduated in values. An impedance can be omitted only in the lead to the first plate of this set.

It can easily be seen that thus the charge of the several plates of the last mentioned set of the condenser is not effected simultaneously as the impedances c, d, e, . . . causes a phase change. The time displacement of the control voltage depends on the value of the alternating current impedances b, c, d, e, . . . which are inserted. In order to retain the amplitudes of the voltages on the separate condenser plates approximately equal, inductive resistances may be inserted in the leads to the condenser plates in addition to the ohmic resistances.

The light controlling cells need not be arranged exactly at right angles to one another but it may be of advantage to cross the cells at an oblique angle. The picture received is then composed of elementary units as shown in Figure 3 in which the individual surface elements have a rhombic shape. In using condenser plates arranged in this manner a smaller rotation of the plane of polarization by the voltages applied to the plates is required.

It has already been mentioned that other electro-optical effects can be used instead of the Kerr effect for controlling the decomposing cell, for example, oscillating crystals can be used instead of the nitro-benzole of the Kerr cell. If alternating current is allowed to act on a cell system composed of oscillating crystals and if the electrical frequency is continually altered within the frequency range fixed by the natural oscillations of the quartz laminae, then only those crystals which are at any time in resonance with the electrical frequency will be set successively into natural vibration. By this means the polarized rays of light passing parallel through the cell only at this point and at this moment are optically altered so that on suitable adjustment of the polarizer and analyzer illumination is effected. As the control frequencies of the second cell system, located at right angles to the first one, are multiples of the first and can be transmitted by means of modulated carrier waves—by wire or wireless methods—to the receiving station together with the picture element frequencies which transmit the light-intensity value, synchronization between the receiver and transmitter is effected.

A crystal cell of this type according to the invention and which may take the place of cell 3 or 4 in Figure 1, is shown diagrammatically in Figure 4 in which the number of the crystals for simplicity is shown much smaller than the actual num-

ber. The oscillations set up by the oscillating circuit 8 of thermionic tube generator 9 are led to the two coatings 10 and 11 of the crystal cell by means of the coupling transformer 12. The crystals 45—52 located 70 between the coatings are of different lengths as can be seen from the drawing, and consequently have different natural vibrations. If the electrical oscillation present in the circuit 8 is continually altered by means 75 of the rotating condenser 13 the individual crystals 5—12 will, as can be seen from the foregoing, be brought in succession into natural oscillation so that a control of the polarized light passing through these crystals can be effected and utilized according to the invention. The same control takes place in the second cell, which according to Fig. 1 is arranged at right angles to the first, the only difference being that the natural oscillations of the crystals and accordingly the control frequencies may be chosen from a different range, and are cyclically applied to the second cell at a rate which is a multiple of the cyclic frequency per 80 time unit at which the different control frequencies are applied sequentially to the first cell.

It is not necessary to use special condenser coatings to separate the individual crystals. 95 Two coatings will suffice for each of the two crosswise disposed decomposing cells between which the whole prism consisting of the separate quartz laminae of different natural oscillations is arranged as is diagrammatically shown by Figure 5 of the drawings which shows one of the two cells. The individual crystal laminae may be laid not only directly on top of one another but may be compressed without detracting from the 100 action of the control frequencies on the optical effect. The individual crystals also oscillate in such a case without any noticeable disadvantageous effect on the adjacent crystals when the whole crystal system is compressed to a higher degree. By this means apart from a small alteration of the natural oscillations of the crystals it only causes the natural oscillations to be damped the resultant advantage being that the crystal 110 system becomes more lag free. The reduction of the oscillation period of the individual crystals, each of which normally requires a very small damping is of importance, particularly in the case of decomposition of the picture into very small units and the consequently required very high velocities of transmission (television) in order to obtain the necessary rapid optical alteration of the light rays passing through the cell. 115

Quartz has been found to be the best piezoelectrical crystal substance for the cells which decompose the picture. Anisotropic crystals of this type have however the disadvantage that they polarize chromatically, 120

i. e. cause a colour change in the light passing through. In order to avoid this effect caused by the so called rotary dispersion, the two decomposing cells are, according to 5 the present invention, constructed so that the chromatic polarization of the one cell is counteracted by the other cell. This can be obtained, for example, by assembling the horizontal crystal system of laevo-rotatory 10 quartz elements, and the vertical crystal system of dextro-rotatory quartz elements as is diagrammatically shown by the arrows in Figure 6. An arrangement of this type shows no chromatic alteration of the white 15 light passing through and allows of a complete extinction and lighting-up of the field of view.

In simplifying the cells for decomposing the picture a further step may be taken by 20 using a coherent or continuous anisotropic crystal, for example a quartz prism converting the whole breadth of the picture, instead of the individual crystal laminae. It is only essential in this case that the crystal 25 structure be such that the individual parallel layers of the crystal can be set in different natural oscillations similarly as in a prism which has been built up.

A piezo-electric crystal may also be used 30 instead of a Kerr cell at point 7 of the receiving station Figure 1 for the light control for differentiating the light intensity value of the individual points of the picture by suitably damping the natural oscillation 35 of the crystal either by pressure or by cementing on an iso-tropic medium (glass).

It is however, not absolutely necessary 40 for a special element of this type (7, Figure 1) to be used at the receiving station for the control of the light intensities. This special element may be dispensed with according to the present invention if one of the two control cells 3, 4 at the receiving station or even both simultaneously under- 45 take the function of the light control element for the individual points of the picture. It is merely necessary that at the transmitting end the currents derived from the photo-cell serve to modulate the cell control 50 currents to be transmitted to the receiving station. In this case there only need to be transmitted from the transmitting end to the receiving end:

1. Control currents for opening the layers 55 of the one cell;

2. Control currents for opening the layers of the other cell.

At the receiving end it is then only necessary to use a constant light source and two 60 light controlling cells. The one cell is excited by one of the two variable control frequencies and the other by the already modulated variable control frequency. Both cell control currents may also be simultaneously modulated by the photo-cell currents so that

both cells at the receiving end are influenced in their optical conditions by the photo-cell of the transmitting end. A common carrier wave of high frequency is used to transmit the control frequencies. The variable control frequencies are demodulated at the receiving station in a manner well known in radio telephony, for example by using a rectifier.

The picture transmitting system is shown 75 diagrammatically in Figures 7 and 8 of the drawings. As the sole purpose is to explain the principle of the invention the illustrations of the high frequency devices are limited to those absolutely necessary. Obviously, all the modulating and amplifying devices used in high frequency technique can here be suitably used.

Figure 7 shows the picture transmitter and Figure 8 the picture receiver.

In Figure 7 a back coupled thermionic tube generator 31 which supplies the carrier wave to the aerial 32 connected therewith is used at the source for producing undamped oscillations. The modulating tube 33 which serves to influence the short carrier waves produced by the thermionic tube 31 is located in the anode circuit of the thermionic tube generator 31. 34 and 35 are two additional thermionic tube generators, in the oscillating circuits of which are located rotating condensers 36 and 37. The two tube generators 34 and 35 together with their variable condensers 36 and 37 provide the variable control frequencies necessary for the two cells 100 38 and 39, which, as can be seen from the drawings, are coupled respectively with the oscillating circuits of the two generators 34 and 35 through the coils 10 and 11. The two condensers 36 and 37 may be connected 105 with one another in such a way that the condenser 37 effects a number of revolutions which is a multiple of that effected by the condenser 36. The ratio of the two speeds of these condensers is adjusted according to 110 the number of the division lines of the picture to be effected by the two cells 38 and 39 and depends also on the fineness of division of the picture and on the size of the two cells 38 and 39. In the case where the 115 number of horizontal respectively vertical strips into which the picture is decomposed by each cell is for example 100, the condenser 37 must rotate 100 times faster than the condenser 36. The frequency range of these 120 two condensers are also different. They depend on the natural oscillations of the individual crystals in the cells 38 and 39 in which connection it is to be noted that the crystals of the decomposing cell 38 have a 125 different natural oscillation from those of the cell 39. The control frequencies produced by the generators 34 and 35 act by means of the two transformers 42 and 43 on the control grids of the modulating ther-

mionic tube 33 which serves to modulate the carrier wave of the transmitter 31. The modulation is however simultaneously altered as can be seen from the drawing, by the 5 photo-cell 14 in such a way that when this cell is obscured from the light rays of the picture to be transmitted and its resistance is infinitely high, no modulation is effected, whilst when the photo-cell is illuminated the 10 modulating currents are more or less altered according to the degree of illumination. It is easily seen from the explanation given above, and in considering Figure 1 in conjunction with Fig. 7, that the light passing 15 from the plane of the picture 15 through the polarizer 16 is controlled by the two cells 38 and 39 according to the variable frequencies produced by the two thermionic tube generators 34 and 35 and by this means 20 the picture is first decomposed into its separate elements. The light values of the individual picture elements pass in succession through the analyzer 17 and reach the photo-cell 14 through the lens 18. The photo-cell 25 14 then causes according to these varying light intensity values, as has been described, an alteration of the carrier wave produced by the tube 31 respectively an alteration of the grid control potential of the tube 33 30 which eventually causes the modulation of this wave.

The carrier wave modulated in this manner arrives at the receiving aerial 19 shown diagrammatically in Figure 8 and is demodulated or rectified in the detector circuit 20. A control of the two cells 38^a and 39^a which is effected synchronously with the control of the two cells 38 and 39 of the transmitter in Figure 7 can then be effected by means of 40 two transformers 21 and 22.

Whilst however, the two cells 38 and 39 of the transmitter are completely opened and closed by the controlling action of the two generators 34 and 35 the opening in the 45 case of the cells 38^a and 39^a of the receiver in Figure 8 is under the control of the control frequency effected by the photo-cell 14. Accordingly the light rays produced by the constant source of light 23 and which 50 reach the cells 38^a and 39^a through the lens 24 and the polarizer 25 are not only affected spacially with respect to the particular point on the screen 27 which they are to illuminate but are simultaneously controlled in their 55 light intensity values by the two cells 38^a and 39^a so that the true reproduction of the transmitted picture 15 is rendered on the plane of the screen 27 through the analyzer 26.

60 While I have described and shown some particular means of transmitting the control currents from photo cell 14 to tube 33, any other means known in the art may be used for directly or indirectly affecting the con-

trolling action of modulator tube 33 by the 65 varying current intensities produced in photo cell 14 by the varying light intensities, within the scope of the present invention.

I claim—

1. In an apparatus for the electrical transmission of pictures or the like, means for de-composing and respectively re-composing the picture, having a light controlling cell 70 consisting of a plurality of thin laminæ of a transparent medium variable as to its optical properties by the application of an electric potential, and means for varying said properties in successive cycles through all of said laminæ.

2. In an apparatus for the electrical transmission of pictures or the like, means for de-composing and respectively re-composing the picture, having a light controlling cell 75 of a transparent laminated medium variable as to its optical properties in accordance with the frequency of electric potentials applied thereto, each of the laminæ being responsive to a different frequency, and means for applying in successive cycles the frequencies within the range to which the group of laminæ contained in the cell is responsive.

3. In an apparatus for the electrical transmission of pictures or the like, means for de-composing and respectively re-composing 80 the picture, having a light controlling cell consisting of a plurality of thin laminæ of piezo-electric crystals, variable as to their optical properties in accordance with the frequency of the electric potentials applied thereto, each of said laminæ being responsive to a different frequency, and means for applying in successive cycles the frequencies within the range to which the group of laminæ contained in the cell is responsive.

4. In an apparatus for the electrical transmission of pictures or the like, means for de-composing and respectively re-composing 85 the picture, having a light controlling cell consisting of a plurality of thin laminæ of quartz, variable as to their optical properties in accordance with the frequency of the electric potentials applied thereto, each of said laminæ being responsive to a different frequency, and means for applying to the cell in successive cycles the frequencies within the range to which the group of laminæ contained in the cell is responsive.

5. In an apparatus for the electrical transmission of pictures or the like, means for de-composing and respectively re-composing 90 the picture, having a light controlling cell, consisting of a plurality of thin laminæ of a medium variable as to its optical properties in accordance with the frequency of electric potentials applied thereto, each of said laminæ being responsive to a different frequency, thin metallic layers disposed be-

- tween the individual laminæ for applying the potentials of varying frequency to said laminæ, and means for applying to the cell in successive cycles the frequencies within the 65 range to which the group of laminæ contained in the cell its responsive.
6. In an apparatus for the electrical transmission of pictures or the like, means for de-composing and respectively re-composing 70 the picture, having a light controlling cell consisting of a plurality of thin laminæ of an optically variable dielectric arranged between electrodes and doubly refracting under the influence of electric potentials 75 applied to said electrodes, and means for varying the optical character of said laminæ in continuous succession through all of said laminæ.
7. In an apparatus for the electrical transmission of pictures or the like, means for de-composing and respectively re-composing 80 the picture, having a light controlling cell consisting of a plurality of thin laminæ of a medium variable as to its optical properties in accordance with the frequency of 85 electric potentials applied thereto, each of said laminæ having a different dimension and being accordingly responsive to a different frequency, means for applying electric 90 potentials to said laminæ and means for varying in continuous cycles the frequencies of said potentials within the frequency range to which the particular group of laminæ is responsive.
- 35 8. In an apparatus for the electrical transmission of pictures or the like, means for de-composing and respectively re-composing the picture comprising two light controlling cells arranged behind each other in the path 95 of the light rays which compose the picture, each cell consisting of a plurality of thin laminæ of a transparent medium variable as to its optical properties by the application 100 of an electric potential, the lamination of both cells being in the direction of the light rays, the lamination of one cell being inclined at an angle to the lamination in the other cell, and means for varying the optical properties of the laminæ in said cells 105 in continuous cyclic succession.
9. In an apparatus for the electrical transmission of pictures or the like, means for de-composing and respectively re-composing the picture comprising two light controlling 110 cells arranged behind each other in the path of the light rays which compose the picture, each cell consisting of a plurality of thin laminæ of a transparent medium variable as to its optical properties by the application 115 of an electric potential of a particular frequency, each lamina responding to a different frequency, the lamination of both cells being in the direction of the light rays, the lamination of one cell being inclined at an 120 angle to the lamination in the other cell, and means for varying the optical properties of the laminæ in said cells in continuous cyclic succession, the medium of which the laminæ of one cell are composed being lævo-rotary quartz, and that of which the laminæ of the other cell are composed 125 being dextro-rotary quartz.
13. In an apparatus for the electrical transmission of pictures or the like, means

- for de-composing and respectively re-composing the picture comprising two light controlling cells arranged behind each other in the path of the light rays which compose the picture, each cell consisting of a plurality of thin laminae of a transparent medium variable as to its optical properties by the application of an electric potential of a particular frequency, each lamina responding to a different frequency, the lamination of both cells being in the direction of the light rays and the lamination of one cell being inclined at an angle to the lamination in the other cell, means for applying in continuous cycles to each cell all frequencies within the range to which the group of laminae contained in the cell is responsive, the number of cycles per time unit applied to one cell being a multiple of the number of cycles applied to the other cell.
14. In an apparatus for the electrical transmission of pictures or the like, means for de-composing and respectively re-composing the picture comprising light controlling cells, each cell consisting of a plurality of thin laminae of a transparent medium variable as to its optical properties by the application of an electrical potential, and means for varying said properties in continuous succession through all of said laminae in each cell said cells being disposed between an optical polarizer and an analyzer.
15. In an apparatus for the electrical transmission of pictures or the like, means for de-composing and respectively re-composing the picture comprising light controlling cells, each cell consisting of a plurality of thin laminae of a transparent medium variable as to its optical properties by the application of an electrical potential, and means for varying said properties in continuous succession through all of said laminae in each cell said cells being disposed between two artificial crystals of sodium nitrate serving as optical polarizers and analyzers.
16. In an apparatus for the electrical transmission of pictures or the like, means for de-composing and respectively re-composing the picture comprising a pair of light controlling cells each at the transmitting and at the receiving station, each cell consisting of a plurality of thin laminae of a transparent medium variable as to its optical properties by the application of an electric potential, and means for varying said properties in continuous succession through all of said laminae in each cell, the cells at the transmitting station serving to de-compose the picture into individual elements and the cells at the receiving station serving to re-compose it, and means for synchronously controlling the application of electric potentials to said cells at the transmitting and receiving station.
17. In an apparatus for the electrical transmission of pictures or the like, means for de-composing and respectively re-composing the picture comprising corresponding light controlling cells each at the transmitting and at the receiving station, each cell consisting of a plurality of thin laminae of a transparent medium variable as to its optical properties in accordance with the frequency of electric potential applied thereto, each lamina being responsive to a different frequency, means for applying in continuous succession to each cell the frequencies within the range to which the group of laminae contained in the cell is responsive, and electric connection between said stations including a carrier wave generated at the transmitting station and modulated in accordance with the control frequencies applied to the cell at that station, for applying corresponding control frequencies synchronously to the corresponding cells at the receiving station.
18. In an apparatus for the electrical transmission of pictures or the like in combination light control cells at the transmitting station each consisting of laminated elements of a transparent medium whose optical properties are variable in accordance with particular electric control impulses applied to it for spacially de-composing the picture into elementary light impulses of different intensity, means for converting said light impulses into elementary electric impulses, means for transmitting said elementary electric impulses to the receiving station, similarly constructed cells at the receiving station for re-composing the picture, a local source of light at the receiving station whose beam is controlled by said cells, means for synchronously applying to the cells at the receiving station the electrical control impulses applied to the corresponding cells at the transmitting station, and means for applying to the receiving station cells simultaneously the received elementary electric impulses representing the de-composed picture to cause the receiving station cells to spacially re-compose the picture from the elementary electric impulses received and to control the intensity of the local light beam passing through said cells in accordance with the intensity of the individual elementary electric impulses received, to give each spacially re-placed picture element its proper light intensity.
19. In an apparatus for the electrical transmission of pictures or the like, means for de-composing and respectively re-composing the picture, comprising corresponding light controlling cells each at the transmitting and at the receiving station, the cells at the transmitting station serving for decomposing the picture into individual elementary light impulses of different intensity, means for converting said impulses into ele-

- mentary electric impulses and means for transmitting said impulses to the receiving station, the cells at the receiving station serving for spacially re-composing the picture, each of the aforementioned cells consisting of a plurality of thin laminæ of a transparent medium variable as to its optical properties in accordance with the frequency of electric potential applied thereto, each 5 lamina being responsive to a different frequency means for applying in continuous succession to each cell the frequencies within the range to which the group of laminæ contained in the cell is responsive, electrical 10 connection between said station for applying corresponding control frequencies synchronously to the corresponding cells at the two stations, the cells at the receiving station being also optically responsive in accordance 15 with the elementary electric impulses received from the transmitting station, and a local source of light at the receiving station whose beam is controlled by said receiving 20 cells in accordance with the varying intensity 25 of said received elementary electric impulses to give each spacially re-placed picture element its proper light intensity.
20. In an apparatus for the electrical transmission of pictures or the like, means for de-composing and respectively re-composing the picture, consisting of a pair of cells each composed of laminæ extending in the direction of the picture rays and whose individual optical transparency is responsive to particular electric conditions applied to each lamina, the lamination of one cell being disposed at an angle to the lamination of the other cells, so that in the direction of the rays the apparent cross-lamination divides the picture into a plurality of spacially defined elements, means for cyclically applying in each cell successively to each lamina the electrical condition which render it transparent, the number of cycles per time unit applied to one cell being the n th multiple of 30 the number of cycles applied to the other cell if n equals the number of laminæ in said other cell. 35
